UNITED STATES PATENT OFFICE

GEORGE W. MORRISON, OF LOWELL, MASSACHUSETTS.

SAFETY-FOOT FOR LADDERS.

1,109,452.

Specification of Letters Patent. Patented Sept. 1, 1914.

Application filed April 16, 1914. Serial No. 832,345.

To all whom it may concern:

Be it known that I, GEORGE W. MORRISON, a citizen of the United States, resident of Lowell, in the county of Middlesex and State of Massachusetts, have made a certain new and useful Invention in Safety-Feet for Ladders; and I declare the following to be a full, clear, and exact description of the same, such as will enable others skilled in the art to which it appertains to make and use the invention, reference being had to the accompanying drawings, and to letters or figures of reference marked thereon, which form a part of this specification.

Figure 1 is a side view of the invention as applied to a ladder. Fig. 2 is a front view of the invention. Fig. 3 is a side view of the same. Fig. 4 is a section on the line 4—4, Fig. 2. Fig. 5 is a detail bottom plan view 20 of the rubber pad.

The object of the invention is to provide an improved foot or bearing for ladders designed for use upon ice or slippery places, and it consists in the novel construction and 25 combination of parts, as hereinafter set forth.

In the accompanying drawings, the numeral 2, indicates the end portion of a ladder rail, to which the foot is designed to 30 be connected by means of a bolt 3, passing through the rail, and through perforations 4, in the oblique, elongated ears 5, of the foot frame or casting 6. These ears are parallel and extend upward in somewhat oblique fashion so as to correspond with the 35 angle of the ladder rail in medium leaning position against a wall. The edges 7, 7, of each ear are both inclined in the same direction or inward toward the wall, from the bottom line of the base 8, and the breadth of 40 the ear is about one-half its height and less than the distance from the base bottom to the bolt hole 4. In the base is formed an oblong rectangular recess or seat 9, through 45 the lateral walls of which are made perforations 10, for transverse bolts 12.

Seated in the recess 9, is the upper part 13, of an oblong rubber foot or pad 14, said upper part being reduced to fit the recess 50 above a rectangular shoulder 15, which extends around the foot, and is usually slightly beveled outward from the reduced upper part 13 to facilitate adjustment to uneven surfaces and provide for elastic compression. The lower edge of the wall of the

recessed base is designed to bear against the inner angle of this shoulder, which is outwardly separated from said base to provide a working interval for the elastic foot. The reduced upper portion 13, is solid, and through it are made transverse holes 16, for the bolts 12, which secure the rubber foot firmly to the casting or base piece 6, yet so that, on removal of the bolts, it can be readily detached for removal or repair.

The lower and larger part 18, of the rubber foot, is provided, underneath, with transverse inclosed recesses 19, more or less angular in cross section, said recesses being severally inclosed and separated by intervening ribs 20, the recesses and ribs being inclosed within the lower flat margin 21, of the rubber foot, said flat margin being normally in the horizontal plane, and flush with the bottoms of the interior ribs 20, of the foot recess. Pressure on the ladder is designed to transmit, through its rails and the foot casting elastic pressure to the bevel shouldered portion of the rubber foot, so as to compress the recessed lower portion 20 and cause it, through consequent reaction and suction or air pressure, to take hold of a smooth or icy pavement or surface in such wise as to hold the ladder securely in position, at whatever angle it may be set. And, 30 because of the narrow lateral spread of the foot, and the prevention of lateral rocking by the transverse bolts, the ladder can be readily detached from the pavement or surface when necessary for its removal. As the 35 breadth and width of the foot approximate these dimensions of the ladder rail, undue obstruction is avoided in piling and sliding ladders one upon another, as is often necessary in the use of these articles in the fire 40 department of a city.

The angular relation of the foot to the ladder rail when in leaning position, is designed to facilitate the use of the narrow foot, as the adjustment of the ladder to different angles can be made while keeping the line of pressure within the base.

I claim:

In a ladder foot, an oblong bottom-recessed base having lateral, vertical, parallel ears provided with edges inclined in the same direction from the bottom line of the base, and a shouldered rubber pad having a solid perforated upper portion engaging the recess of said base, a circumscribing out-

ward and downward sloping shoulder angularly engaging the wall of said recess, to provide a working interval, and an elongated lower portion having a series of separately 5 inclosed bottom recesses having marginal separating ribs within an inclosing wall, said wall and ribs having their bottom edges in the same horizontal plane, and transverse

parallel bolts for connecting the ladder, the pad and the base.

10

In testimony whereof I affix my signature, in presence of two witnesses.

GEORGE W. MORRISON.
